FLOOR COVERING OR SIMILAR ARTICLE

Joseph Robert Cecchine, Manville, N.J., assignor to Johns-Manville Corporation, New York, N.Y., a corporation of New York

Filed Mar. 4, 1968, Ser. No. 10,820

Term of patent 14 years

Int. Cl. D25—01

U.S. Cl. D18—2

FIG. 1

FIG. 2

FIG. 3

FIG. 1 is a plan view of a floor covering or similar article showing a full repeating unit;

FIG. 2 is a plan view of a floor covering or similar article showing a modification of the full repeating unit of FIG. 1, wherein portions of the unit contain fissure-like markings; and

FIG. 3 is a plan view of a floor covering or similar article showing another modification of the full repeating unit of FIG. 1, wherein portions of the unit contain fissure-like markings, such portions substantially corresponding to the portions of FIG. 2 which do not contain fissure-like markings.

The floor covering is of conventional thickness.

I claim:

The ornamental design for a floor covering or similar article, as shown and described.
